Daniel A Doran

BY

Howard C Thompson

ATTORNEY

UNITED STATES PATENT OFFICE.

DANIEL A. DORAN, OF YONKERS, NEW YORK.

MAIL ELEVATOR.

Application filed October 2, 1923. Serial No. 666,077.

To all whom it may concern:

Be it known that I, DANIEL A. DORAN, a citizen of the United States, and residing at Yonkers, in the county of Westchester and State of New York, have invented certain new and useful Improvements in Mail Elevators, of which the following is a specification, such as will enable those skilled in the art to which it appertains to make and use the same.

This invention relates to mail elevators or lifts, and particularly to apparatus of this class designed for use in raising and lowering mail in an apartment house or other building or dwelling; and the object of the invention is to provide an apparatus of the class specified by means of which mail or small packages or objects may be automatically moved from predetermined points in a building to a single room or compartment, for example, a master mail box, and also automatically return to predetermined points in the building; a further object being to provide an apparatus involving one electric motor or other power element, actuating a plurality of mail box units in such manner as to move all of such units from predetermined points in a building to one delivery point and vice versa, by the employment of suitable speed transmission means; a still further object being to provide automatically actuated means for controlling the operation of the electric motor or other power element; and with these and other objects in view, the invention consists in an apparatus of the class and for the purpose specified which is simple in construction and operation, efficient in use and which is constructed as hereinafter described and claimed.

The invention described and claimed herein is an improvement on that shown and described in my pending applications bearing the following numbers and dates, Ser. No. 384,398 filed May 26, 1920, which has matured into Patent No. 1,501,529, July 15, 1924, Ser. No. 600,012 filed November 10, 1922, Ser. No. 605,788 filed December 9, 1922, and is fully disclosed in the following specification, of which the accompanying drawing forms a part, in which the separate parts of my improvement are designated by suitable reference characters in each of the views and in which:—

Fig. 1 is a diagrammatic view showing one method of carrying my invention into effect, with parts of the construction broken away and in section.

Fig. 2 is a partial section on the line 2—2 of Fig. 1.

Fig. 3 shows two diagrammatic views of the electric circuit which I employ with the devices of such circuit in different positions

Fig. 4 is a partial section on the line 4—4 of Fig. 2; and,

Fig. 5 is a detail view of a part of the construction shown in Fig. 1.

In the drawing I have shown for the purpose of illustrating one use of my invention or one method of carrying it into effect, four mail elevator tubes 10, said tubes all being of different lengths or the top portions thereof lead to different floors or parts of a building, while the lower end portions of said shafts all meet in a common plane or register with openings 11 at the bottom portion of said shafts. A master mail box door 12 controls the admission to all of said shafts or the apertures 11 therein, said door being controlled by a lock 13 having a switch portion 14 actuated thereby. In the separate shafts 10 are mounted mail boxes 15 similar in construction to the mail boxes shown in my pending application bearing Serial No. 605,788, and filed December 9, 1922, said box being elongated and rectangular in form and comprising side walls 15^a and an arc-shaped back wall 15^b, a bottom 15^c and a spring member 15^d for retaining letters or the like in the mail box, and the corner portions of the box 15 are provided with outwardly bowed rod members 16 to facilitate the movement of the box in the shafts and all of the boxes are of similar construction. Connected with the top and bottom of each mail box 15 is a belt, chain or cable 17 which passes around a pulley or the like 18 at the upper end of the shaft and around a similar pulley or the like 19 at the bottom of the shaft and preferably a predetermined distance therebelow. The belt is also preferably passed around a similar pulley 20 positioned directly above the pulley 19 to retain the belt 17 against displacement from the pulley 19. It will be understood that each of the shafts are similarly constructed or provided with the pulleys 18, 19 and 20, and as shown in

95
100
105

Fig. 1 of the drawing the pulleys 19 of the separate shafts are mounted on a shaft 21 while the pulleys 20 are mounted on a shaft 22. The shafts 21 and 22 are mounted in 5 suitable bearings 23 and mounted in said bearings below the shaft 21 is another shaft 24 on which are mounted a plurality of gears 25, 26, 27 and 28 and which increase in size respectively. Mounted on the 10 shaft 21 and in position to mesh with the gears 25 to 28 inclusive are gears 29, 30, 31 and 32 which decrease in size respectively and the gears 29 to 32 inclusive are coupled with the pulleys 19 mounted on the shafts, 15 and said pulleys and gears are free to rotate on said shafts, and by reason of the gear construction employed, the four pulleys 19, in the construction shown, will be rotated at different speeds by reason of the 20 ratio of gearing employed.

For rotating the shaft 24 which constitutes the drive shaft, I employ an electric motor 33 capable of rotation in two directions; that is to say, clockwise and anti- 25 clockwise and the motor shaft extends into a housing 34 in which is suitable gearings to rotate a shaft 35 positioned at right angles to the motor shaft and on said shaft is a gear 36 which meshes with a gear 37 on 30 the shaft 24 as clearly shown in Fig. 5 of the drawing. With this construction, the operation of the motor 33 in one direction will cause the shaft 34 to be rotated in one direction to either raise or lower the mail 35 boxes 15 in the separate shafts, and the reverse action of the motor shaft will reverse the movement imparted to said mail boxes as will be apparent. It will also be understood that by reason of the differential 40 speeds of the separate pulleys 19, the same will compensate for the raising and lowering of the mail boxes which extend to different floors or levels in a building; that is to say, the mail box in the shaft 10 to the 45 left of Fig. 1 will travel at slow speed while the mail box in the shaft 10 at the right of Fig. 1 will travel at high speed.

To control the operation of the motor 33, I provide an electric circuit which may be 50 arranged in each of the shafts 10, but in the construction shown a single circuit is employed. The aforesaid electric circuit is composed of two independent and yet co-operative circuits 38 and 39 and both of 55 these circuits have a common source of electrical supply 40. In the circuit 38 is a switch device 41 comprising two contact members 42 adapted to be coupled together by a switch member 43. The switch member 43 is carried by one of inwardly directed side extensions 12^a on the door 12 which controls the admission to the mail boxes in the separate chutes 10, and the circuit is closed through the switch device 60

41 when the door 12 is in an open position. 65 Another switch 44 is mounted in the circuit 38, and this switch is actuated in one direction by a trip device 45 at the lower end of one of the mail boxes 15 as shown in Fig. 2 of the drawing and is moved into 70 an operative or closed position by a spring 46.

In the circuit 39 is a key-controlled switch device 47 which is actuated by the lock mechanism 13 on the door 12, the circuit 75 being closed by the switch portion 14 as will be apparent. In the circuit 39 is another switch device 48 normally held in an operative position by a spring 49 and adapted to be moved into an inoperative position 80 by a trip device 50 on the top of the mail box 15.

Normally the mail boxes are all in their uppermost positions in the shafts 10 and in juxtaposition to doors or openings communicating with said shafts, one of said doors being indicated at 51 in Fig. 1 of the drawing, and in this position of the apparatus, the circuits 38 and 39 or the switch devices therein will assume the position 90 shown at the bottom of Fig. 3; that is to say, the switch 41 is open, the switch 44 closed, the switch 47 closed and the switch 48 open. Now, if the door 12 be opened by 95 a letter carrier, the switch 41 will be closed to complete the circuit 38 to the motor 33, which operation rotates the motor in a direction to lower all of the mail boxes into juxtaposition with the opening controlled by the door 12, and in this operation, the downward movement of the mail box provided with the trip device 50 will release the switch 48, and this switch will be moved into a closed position by the spring 49, but the circuit 39 will remain open by reason 100 of the opening of the door 12.

When the mail boxes have reached their lowermost position, the circuit 38 to the motor 33 is broken by the trip 45 engaging the switch 44 to move the same into inoperative position, and this position of the parts is shown at the top of Fig. 3 of the drawing. The operation of closing the door 12 by the letter carrier after the mail has been placed in the respective boxes 15, will break the circuit 38 through the switch 41 and the circuit 39 will be closed through the switch 47. The motor 33 will thus be operated in the reverse direction and the mail boxes raised to their uppermost position, in which operation the switch 44 will again be closed and the circuit 39 broken by the opening of the switch 48, which is moved into inoperative position by the trip device 50.

From the foregoing, it will be apparent that with my improved apparatus, mail or other packages may be delivered to predetermined floors or compartments on different

floors of a building, automatically by the opening and closing of the master door 12 by an authorized party or parties, the mail boxes being normally in their uppermost 5 positions and being automatically moved downwardly and then automatically moved upwardly in the opening and closing of the door 12. The door 12 is also preferably provided with supplemental door members 12^b 10 which communicate with the lower end portions of the separate shafts 10. Below the door 12 and the shafts, 10, I also preferably provide a large chamber 52 the admission to which is controlled by a door 53, and the 15 chamber 52 may be used for storing magazines or other large packages that cannot be placed in the mail boxes 15.

It will be understood that one of the distinctive features of my present invention 20 resides in the provision of a single power unit, namely the motor 33, for actuating a multiplicity of independent mail boxes to move the same upwardly and downwardly through shafts which lead to various points 25 in a building, and the provision of a transmission of speeds from a drive shaft to driven members whereby the distance traveled by the respective boxes may vary. It will also be understood that the shafts 10 may be 30 of any shape or form and may extend vertically, horizontally or diagonally through a building or the walls thereof as is shown and described by me in my copending applications, and various changes in and modifications of the construction herein shown 35 and described may be made within the scope of the appended claims without departing from the spirit of my invention or sacrificing its advantages.

Having fully described my invention, what I claim as new and desire to secure by Letters Patent, is:—

1. An apparatus of the class described 45 comprising an endless conveyor, a carrier mounted in connection with said conveyor, means involving a power unit and transmission for actuating said conveyor to move said carrier from one point to another, said last named means being automatically controlled, and means involving said first named 50 means for reversing the direction of travel of said carrier.

2. An apparatus of the class described 55 comprising a plurality of conveyors, carriers mounted in connection with the separate conveyors, and means involving a power unit and transmission mechanism for actuating said conveyors and for moving the carriers of the separate conveyors at different speeds.

3. An apparatus of the class described 60 comprising a plurality of conveyors, carriers mounted in connection with the separate conveyors, means involving a power

unit and transmission mechanism for actuating said conveyors and for moving the carriers of the separate conveyors at different speeds, and means for automatically controlling the direction of movement imparted to said carriers.

4. An apparatus of the class described 70 comprising a plurality of conveyors, carriers mounted in connection with the separate conveyors, means involving a power unit and transmission mechanism for actuating said conveyors and for moving the carriers of the separate conveyors at different speeds, and means for automatically controlling the direction of movement imparted to said carriers and for holding said carriers 75 at rest in two different positions thereof.

5. A mail elevator apparatus of the class 80 described comprising a plurality of independent conveyors, mail boxes mounted in connection with said conveyors and movable thereby, a power shaft, means for rotating said shaft in two directions, and means for transmitting the rotation of said power shaft to the separate conveyors to operate the same 85 as different speeds.

6. A mail elevator apparatus of the class 90 described comprising a plurality of independent conveyors, mail boxes mounted in connection with said conveyors and movable thereby, a power shaft, means for rotating said shaft in two directions, means for transmitting the rotation of said power shaft to the separate conveyors to operate the same at different speeds, and means for automatically controlling the operation of the apparatus.

7. A mail elevator apparatus of the class 95 described comprising a plurality of independent conveyors, mail boxes mounted in connection with said conveyors and movable thereby, a power-shaft, means for rotating said shaft in two directions, means for transmitting the rotation of said power shaft to the separate conveyors to operate the same at different speeds, and means for automatically controlling the operation of the apparatus and for regulating the direction in 100 which the mail boxes are actuated.

8. A mail elevator apparatus of the class 110 described comprising a plurality of independent shafts, the lower end portions of said shafts terminating at a predetermined point, a door controlling the communications to the lower end portions of said shafts, mail boxes mounted to move upwardly and downwardly in said shafts, means for actuating said boxes comprising endless conveyors, a reversible electric motor, a power shaft driven by said motor, and means for transmitting relative movements to the separate conveyors and mail boxes in the rotation of said power shaft.

9. A mail elevator apparatus of the class

described comprising a plurality of independent shafts, the lower end portions of said shafts terminating at a predetermined point, a door controlling the communications to the lower end portions of said shafts, mail boxes mounted to move upwardly and downwardly in said shafts, means for actuating said boxes comprising endless conveyors, a reversible electric motor, a power shaft driven by said motor, means for transmitting relative movements to the separate conveyors and mail boxes in the rotation of said power shaft, said motor being in an electric circuit, and means in said circuit for automatically controlling the operation or rotation of said motor.

10. A mail elevator apparatus of the class described comprising a plurality of independent shafts, the lower end portions of said shafts terminating at a predetermined point, a door controlling the communications to the lower end portions of said shafts, mail boxes mounted to move upwardly and downwardly in said shafts, means for actuating said boxes comprising endless conveyors, a reversible electric motor, a power shaft driven by said motor, means for transmitting relative movements to the separate conveyors and mail boxes in the rotation of said power shaft, said motor being in an electric circuit, and means in said circuit for automatically controlling the operation or rotation of said motor and whereby said mail boxes may be retained at rest in two positions thereof.

11. A mail elevator apparatus of the class described comprising a plurality of independent shafts, the lower end portions of said shafts terminating at a predetermined point, a door controlling the communications to the lower end portions of said shafts, mail boxes mounted to move upwardly and downwardly in said shafts, means for actuating said boxes comprising endless conveyors, a reversible electric motor, a power shaft driven by said motor, means for transmitting relative movements to the separate conveyors and mail boxes in the rotation of said power shaft, said motor being in an electric circuit, and means in said circuit for automatically controlling the operation or rotation of said motor and whereby said mail boxes may be retained at rest in two positions thereof, said circuit being controlled by the opening and closing of said door.

12. In a mail elevator apparatus of the class described involving a plurality of shafts, mail boxes mounted in said shafts and movable from one end portion thereof to the other, an operating mechanism for actuating said mail boxes, said mechanism comprising a power shaft, an electric motor geared in connection with said shaft and adapted to rotate the same in two directions,

and a plurality of driven members geared in connection with said power shaft in such manner as to be driven at a predetermined ratio of speed with reference to said power shaft.

13. In a mail elevator apparatus of the class described involving a plurality of shafts, mail boxes mounted in said shafts and movable from one end portion thereof to the other, an operating mechanism for actuating said mail boxes, said mechanism comprising a power shaft, an electric motor geared in connection with said shaft and adapted to rotate the same in two directions, and a plurality of driven members geared in connection with said power shaft in such manner as to be driven at a predetermined ratio of speed with reference to said power shaft and with reference to each other.

14. In a mail elevator apparatus of the class described involving a plurality of shafts, mail boxes mounted in said shafts and movable from one end portion thereof to the other, an operating mechanism for actuating said mail boxes, said mechanism comprising a power shaft, an electric motor geared in connection with said shaft and adapted to rotate the same in two directions, a plurality of driven members geared in connection with said power shaft in such manner as to be driven at a predetermined ratio of speed with reference to said power shaft and with reference to each other, and means for automatically starting and stopping said electric motor.

15. In a mail elevator apparatus of the class described involving a plurality of shafts, mail boxes mounted in said shafts and movable from one end portion thereof to the other, an operating mechanism for actuating said mail boxes, said mechanism comprising a power shaft, an electric motor geared in connection with said shaft and adapted to rotate the same in two directions, a plurality of driven members geared in connection with said power shaft in such manner as to be driven at a predetermined ratio of speed with reference to said power shaft and with reference to each other, and means for automatically starting and stopping said electric motor and for reversing the direction of its rotation.

16. In an apparatus of the class described a power transmission mechanism comprising a power element, a power shaft driven by said element, a plurality of members in operative connection with said shaft and adapted to be driven at different speeds.

17. In an apparatus of the class described a power transmission mechanism comprising a power element, a power shaft driven by said element, a plurality of members in operative connection with said shaft and adapt-

ed to be driven at different speeds, and said power shaft being rotated by the power unit clockwise and anti-clockwise.

18. In an apparatus of the class described, 5 a power transmission mechanism comprising a power unit, a power shaft adapted to be rotated by said unit clockwise and anti-clockwise, a plurality of gears mounted on the power shaft, said gears having different

pitch diameters with reference to each other, 10 and members in operative connection with said gears and adapted to be actuated at predetermined speeds.

In testimony that I claim the foregoing as my invention I have signed my name this 15 29th day of September 1923.

DANIEL A. DORAN.
